UNITED STATES PATENT OFFICE.

GEORGE H. HAYES AND HENRY K. NASH, OF DE RUYTER, NEW YORK.

FOLDING WASH-BENCH.

SPECIFICATION forming part of Letters Patent No. 391,247, dated October 16, 1888.

Application filed March 30, 1888. Serial No. 268,951. (No model.)

To all whom it may concern:

Be it known that we, GEORGE H. HAYES and HENRY K. NASH, respectively, of De Ruyter, county of Madison, in the State of New York, 5 and citizens of the United States, have invented certain new and useful Improvements in Folding Wash-Benches, of which the following is a specification, reference being had to the accompanying drawings, in which—

10 Figure 1 is a central vertical longitudinal section in unfolded position; Fig. 2, a top plan and partly sectional view, unfolded position, taken on line xx , Fig. 1; and Fig. 3, a side elevation, the parts being folded.

15 Similar letters of reference indicate corresponding parts throughout the several views.

The object of our invention is to produce a folding wash-bench of simple and cheap, yet strong, construction, that may be easily 20 and expeditiously folded or unfolded and which will fully and completely meet all requirements, for the reason that when unfolded it serves as an excellent wash-bench and can quickly be folded together into a very small 25 compass and is therefore invaluable in households.

It consists in the several novel features of construction hereinafter described, and specifically enumerated in the claim hereto annexed.

30 It is constructed as follows:

A A are upright standards rigidly connected together by the flat cross-piece a and rounds $b b$ and c . At the upper portion of the respective standards A we form parallel vertical slotways B B, substantially as shown, to 35 which we both movably and pivotally connect the bracing and supporting legs C C by their pivots $d d$, which project through the slotways and are provided with heads $e e$ to retain the 40 upper portion of the legs at the slotways, and the rounds K serve to brace the legs at their lower extremity.

D D are the tub supporting platforms, consisting of the longitudinal strips ff , having 45 transverse rounds connecting them together. Each of said platforms D is pivotally connected to the standards A by pivots $g g$, formed at the ends of the rounds $b b$ and inserted in said standards, and the platforms are pivotally 50 connected to the supporting-legs by pivots $h h$, formed at the end portions of the rounds

$i i$ and passing loosely through the strips ff and inserted in the supporting-legs.

The cross-piece a , in conjunction with the inclined strips a' at either side thereof, is designed as a support for a wringer, the wringer being clamped to the flat cross-piece, and when in use the water expressed from clothing by the wringer will drop onto the inclined strips and thence fall into the tubs. The strips 60 having a corresponding inclination on their lower as well as upper face, it is obvious that all drippings must drop directly into the tubs.

Either one or both the platforms may be unfolded for service, as is deemed desirable. In 65 either case strength and stability of the bench are assured.

To fold the parts together, the platforms are swung upward on their pivots, whereupon the upper portion of the supporting legs or 70 braces pass upward in line with the slotways, while the lower extremities move both upward and inclining inward toward the standards, all as clearly indicated by arrows in Fig. 1 of the drawings. 75

It will be observed that, aside from the fact that either one single platform, or both conjointly, of our device may be unfolded for service, the parallel slotways being formed at the top portion of the standards, instead of at 80 the bottom, all liability of weakening the base portions (as would be the case were the slotways placed there) is entirely obviated; furthermore, that the lower extremities of the supporting and bracing legs, during either the 85 operation of folding or unfolding the bench parts, do not drag nor scrape upon the floor, but only come in direct contact therewith when the bench is in position for usage; also that in the operation of folding the various 90 parts together the standards are not raised up off from the floor, but, on the contrary, rest firmly thereon and thus support the entire weight of the connected parts when folded.

Having described our invention, what we 95 claim as new, and desire to secure by Letters Patent, is—

In a folding wash-bench, the combination, with vertical supporting-standards provided, respectively, with a pair of parallel vertical 100 slotways at their top portion, of a pair of supporting legs or braces, each pivotally and

movably connected at its upper end to the opposite slotways at one side of the respective standards, and a similar pair of supporting legs or braces correspondingly connected to opposite slotways at the other side of said standards, said respective pairs being pivotally connected part way their length to supporting platforms, which are respectively pivotally secured to rigid bearings in the supporting standards, substantially as described.

In witness whereof we have hereunto set our hands this 6th day of March, 1888.

GEORGE H. HAYES. [L. S.]
HENRY K. NASH. [L. S.]

In presence of—
RICHARD DRAPER,
FRANK D. SIMONS.
